CLAIM

The ornamental design for a lid for a container, as shown and described.

DESCRIPTION

FIG. 1 is a top front right perspective view of a first embodiment of a lid for a container, showing our new design in condition of use;

FIG. 2 is an enlarged top front perspective view of the lid for a container shown in FIG. 1;

FIG. 3 is a top rear perspective view of the lid for a container shown in FIG. 2;

FIG. 4 is a front view of the lid for a container shown in FIG. 2;

FIG. 5 is a rear view of the lid for a container shown in FIG. 2;

FIG. 6 is a left side view of the lid for a container shown in FIG. 2;

FIG. 7 is a right side view of the lid for a container shown in FIG. 2;

FIG. 8 is a top view of the lid for a container shown in FIG. 2;

FIG. 9 is a bottom view of the lid for a container shown in FIG. 2;

FIG. 10 is a top front perspective view of a lid for a container, illustrating the lid in an open position;

FIG. 11 is a top rear perspective view of the lid for a container shown in FIG. 10;

FIG. 12 is a front view of the lid for a container shown in FIG. 10;

FIG. 13 is a rear view of the lid for a container shown in FIG. 10;

FIG. 14 is a left side view of the lid for a container shown in FIG. 10;

FIG. 15 is a right side view of the lid for a container shown in FIG. 10;

FIG. 16 is a top view of the lid for a container shown in FIG. 10;

FIG. 17 is a bottom view of the lid for a container shown in FIG. 10;

FIG. 18 is a top front right perspective view of a second embodiment of a lid for a container;

FIG. 19 is a top rear perspective view of the lid for a container shown in FIG. 18;

FIG. 20 is a front view of the lid for a container shown in FIG. 18;

FIG. 21 is a rear view of the lid for a container shown in FIG. 18;

(Continued)

FIG. 22 is a left side view of the lid for a container shown in FIG. 18;
 FIG. 23 is a right side view of the lid for a container shown in FIG. 18;
 FIG. 24 is a top view of the lid for a container shown in FIG. 18;
 FIG. 25 is a bottom view of the lid for a container shown in FIG. 18;
 FIG. 26 is a top front perspective view of a lid for a container, illustrating the lid in an open position;
 FIG. 27 is a top rear perspective view of the lid for a container shown in FIG. 26;
 FIG. 28 is a front view of the lid for a container shown in FIG. 26;
 FIG. 29 is a rear view of the lid for a container shown in FIG. 26;
 FIG. 30 is a left side view of the lid for a container shown in FIG. 26;
 FIG. 31 is a right side view of the lid for a container shown in FIG. 26;
 FIG. 32 is a top view of the lid for a container shown in FIG. 26; and,
 FIG. 33 is a bottom view of the lid for a container shown in FIG. 26.
 In the drawings, the broken lines depict environmental subject matter only and form no part of the claimed design.
